DESIGN FOR A BADGE OR THE LIKE

Mary Margaret Greer and Charles C. Greer,
Johnstown, Pa.

Application August 5, 1941, Serial No. 102,698

Term of patent 7 years

To all whom it may concern:

Be it known that we, Mary Margaret Greer and Charles C. Greer, citizens of the United States, residing at Johnstown, in the county of Cambria, State of Pennsylvania, have invented a new, original, and ornamental Design for Badges or the like, of which the following is a specification, reference being had to the accompanying drawing, forming part thereof.

In the accompanying drawing:

The drawing is lined for color.

We claim:

The ornamental design for a badge or the like, substantially as shown and described.

MARY MARGARET GREER.
CHARLES C. GREER.
